COMBINED CARD CASE AND WALLET

Joseph K. Seitz, Sunland, Calif., assignor to Bri-Son Company, Inc., Los Angeles, Calif., a corporation of California

Filed Sept. 28, 1959, Ser. No. 57,705

Term of patent 14 years

(Cl. D87—3)

FIG. 1.

FIG. 2.

FIG. 3.

FIG. 4.

Fig. 1 is a perspective view of a combined card case and wallet in closed position showing my new design;

Fig. 2 is a front perspective view of my combined card case and wallet in open position;

Fig. 3 is a rear perspective view of my combined card case and wallet in open position; and

Fig. 4 is a reduced scale front perspective view of my combined card case and wallet in a different open position than that shown in Fig. 2.

I claim:

The ornamental design for a combined card case and wallet, as shown.
